UNITED STATES PATENT OFFICE.

CORREL W. JOHNSON, OF NEW YORK, N. Y.

SOUND CLARIFIER.

Application filed June 15, 1922. Serial No. 568,587.

To all whom it may concern:

Be it known that I, CORREL W. JOHNSON, a citizen of the United States, and resident of the city of New York, borough of Manhattan, county of New York, and State of New York, have invented a new and Improved Sound Clarifier, of which the following is a full, clear, and exact description.

My invention relates to a sound clarifier, 10 and aims to provide a device of this nature presenting certain improved construction over my previous application, Patent No. 1447855, dated March 6, 1923, entitled Sound clarifier, as well as my previous Patent 15 #1240050 issued September 11, 1917, also application Serial No. 568586, filed June 15, 1922, entitled Sound amplifier.

It is an object of the present invention to provide a sound clarifier, particularly intended for projection of sound waves, such as occurs in connection with talking machines, although my invention is not necessarily limited to this particular association.

The present invention further contemplates the provision of a sound clarifier which will embody extremely simple construction, and present a body which will insure a circulation of air in such a manner as to induce a clarification of the sounds 25 and to prevent muffling of the same.

A still further object of this invention is that of constructing a device of the character stated which will serve to merge all sound waves passing through the same into 30 each other, and which will further prevent the formation of echos, nasal or inharmonious sounds, and in which the tone will be amplified and clarified to thus produce the best possible results.

With these and further objects in mind 35 the present invention embraces a sound clarifier comprising a body in which parts movable with respect to each other, will be eliminated, and in which any abrupt surfaces will be eliminated, together with means within the body for achieving the objects set forth in the last paragraph.

Reference is had to the attached sheet of drawings in which a practical embodiment 40 of my invention has been shown, and in which it will be seen that I have shown my clarifier associated with a talking machine.

Figure 1 is a sectional side view of a conventional talking machine and showing my 45 improved type of clarifier associated therewith, and

Figure 2 is a sectional plan view taken along the line 2—2 and in the direction of the arrows indicated in Figure 1.

It will be seen in these views that the reference numeral 5 indicates the lid of a talking machine, and 6 the cabinet, which in the usual manner has been provided with a turn table 7 with which a reproducer 8 operates, the latter being in turn connected to a tone arm 9 which is supported in such a manner as to throw the sound waves passing through its body, into my improved type of clarifier.

Now with respect to the sound clarifier, 50 it will be noted that the essence of my invention consists in the provision of a device of this nature which will present a body having a passage which includes no abrupt turns or angles. Thus the reference numeral 10 identifies the intake end of the clarifier, and 11 the outlet end thereof, the body of the clarifier tapering throughout its entire length, and presenting a wall 12 formed with a passage 13. This passage, as has 55 been clearly shown in Figure 2 presents a flaring mouth or inlet 14 which, due to its disposition in the body of the clarifier, will serve to divert a portion of the sound waves into the passage 13.

More particularly it will be noted that the mouth 14 of the passage 13 takes on a parabolic formation at its inset with the thicker wall 12, and beginning at its greater cross section it points adjacent the side walls of the sound conveyor, becomes a converging oblique depression carrying a concave formation to its outlet, the edges of the concave depression being rounded to provide a smooth passage for the air motions conveying the sound waves in their progressive course through said sound conveyor, through said auxiliary opening, it being noted that the latter is in connection with a tube or horn suspended within said clarifier and 80 adjacent the outer end of the same.

With respect to the tube or horn aforementioned it will be noted that the same includes a body 15 which is preferably polygonal and flared towards the outer end 11 of the clarifier. Adjacent the base of the body I provide a wall 16 disposed at an angle which will insure an even and desirable flow of the sound waves. A tube 17 has its outer end in communication with an opening in the body 15 at a point adjacent the inner end of the said wall 16 and the inner end of 85 90 95 100 105 110

this tube is suitably connected to the thickened wall 12 of the clarifier, and at a point adjacent to the outlet end of the passage 18 it being noted that the horn 15 receives its only support from the tube 17 which in turn is supported by the thickened wall 12.

It will also be noted that the inner surface of the thicker wall takes a horizontal course and has an elliptical protuberance 18 adjacent to its outlet, and by means of this construction a sufficient body is provided at this point to permit of the attachment of the inner end of the tube 17 which surrounds the outlet of the auxiliary opening or passage 13. It is further to be noted that the thicker wall thereafter terminates in an inclined plane as at 19 to meet with or merge into the wall of the amplifying chamber of the clarifier to thus avoid creating a pocket in the sound waves during the course of their propagation.

It will be understood that by a construction of this nature the objects of this invention are accomplished and further incident to the provision of the horn body or tube 15 within the clarifier, and due to the relative size of these elements, the former will be more in sympathy with certain sound waves than the latter to thus more clearly reproduce the sound waves.

Thus it will be seen that all the results attributed to this invention are accomplished and it will be appreciated that numerous modifications of structure might readily be resorted to without in the least departing from the scope of my claims; which are:

1. A sound clarifier including a body hav-

ing a bore, a thickened wall forming a part of said body and being provided with a passage, and a tube connected to said passage adjacent its outer end.

2. A sound clarifier including a body having a main bore, a passage formed in said body portion, the body portion formed with thickened walls near the forward end of said passage, and a tube connected to the body portion at the outer end of said passage, said passage having a flaring inner end.

3. A sound clarifier including a body formed with a bore, a tube connected to the outer end of said bore to provide a continuation thereof, a horn connected to the outer end of said tube, and a wall within said horn arranged at an angle to the direction of the passage within the tube at the point of connection to said horn.

4. A sound clarifier including a body formed with a bore, a thickened wall forming a part of said body and being provided with a passage, a tube connected to the outer end of said passage, and a portion of said thickened wall being extended beyond the point of connection of said tube with said passage.

5. A sound clarifier including a body formed with a bore, the forward lower end of said body being thickened and provided with a passage along said thickened portion, a tube connected to the end of said thickened portion to form a continuation of said passage, and a horn connected to the outer end of said tube and laterally supported thereby.

CORREL W. JOHNSON.
